(57) **CLAIM**

The ornamental design for an aircraft navigation and anti-collision light, as shown and described.

DESCRIPTION

FIG. 1 is an isometric view of the front of the aircraft navigation and anti-collision light as it might appear mounted on an aircraft wing.

FIG. 2 is an isometric view of the rear of the aircraft navigation and anti-collision light as it might appear mounted on an aircraft wing.

FIG. 3 is a view from above of the aircraft navigation and anti-collision light.

FIG. 4 is a left side view of the aircraft navigation and anti-collision light. The right side view is not shown as it is a mirror image of the left side view.

FIG. 5 is a front end view of the aircraft navigation and anti-collision light; and,

FIG. 6 is a rear view of the aircraft navigation and anti-collision light.

The broken line showing a portion of the aircraft is included for the purpose of illustrating a portion of the aircraft only and forms no part of the claimed design.

The aircraft navigation and anti-collision light is characterized by a cover and a base. In FIGS. 1-6, the interior lines have been left out to avoid a confusion of lines.

1 Claim, 3 Drawing Sheets
